UNITED STATES PATENT OFFICE.

FREDERICK A. KOLSTER, OF PALO ALTO, CALIFORNIA, ASSIGNOR TO FEDERAL TELEGRAPH COMPANY, OF SAN FRANCISCO, CALIFORNIA, A CORPORATION OF CALIFORNIA.

RADIO RECEIVING APPARATUS.

Application filed June 24, 1926. Serial No. 118,247.

My invention relates broadly to radio receiving apparatus and more particularly to a loop antenna system for radio broadcast receiving sets.

One of the objects of my invention is to provide a construction of loop antenna which may be readily mounted with respect to the cabinet of a radio receiving apparatus and conveniently arranged with respect to the cabinet while permitting rotative movement of the loop for directive reception.

Another object of my invention is to provide a mounting for a loop antenna upon a radio receiving apparatus cabinet where the loop antenna is arranged for combined translatory and rotative movement for varying the position of the plane of the loop for selective reception of signals broadcast from transmitting stations located in different directions.

Another object of my invention is to provide a mechanical mounting for a loop antenna of relatively large size upon the apparatus cabinet which houses broadcast radio receiving apparatus where the loop may be withdrawn from the cabinet structure to a position where it may be rotated in different planes for the selective reception of signals from a particular direction.

Still another object of my invention resides in the construction and arrangement of a loop antenna for a radio broadcast receiving apparatus where means are provided for mounting the loop with respect to the apparatus cabinet by which combined sliding and rotative movement may be imparted to the loop for adjusting the plane of the loop with respect to a desired transmitting station.

Other and further objects of my invention will be understood from the specification hereinafter following by reference to the accompanying drawings in which:

Figure 1 is a front elevation partially broken away and in section showing a fragmentary portion of a radio cabinet equipped with the loop structure; Fig. 2 is a cross-sectional view taken through the frame of the loop on line 2-2 of Fig. 1; Fig. 3 is a view of the loop structure taken on line 3-3 of Fig. 1; Fig. 4 is a cross-sectional view through the loop structure on line 4-4 thereof; Fig. 5 is a cross-sectional view taken through the frame of the loop upon line 5-5 of Fig. 3; Fig. 6 is a plan view

partially broken away of the bracket and sleeve mounting by which slidable movement of the frame of the loop may be effected; Fig. 7 is a side elevation of the bracket and sleeve mounting illustrated in Fig. 6; Fig. 8 is a cross-sectional view through the sleeve mounting on line 8-8 of Fig. 7; Fig. 9 is a detailed view showing the pivotal mounting of the frame of the loop; Fig. 10 is a cross-sectional view showing the assembled bracket sleeve and slide of the loop mounting; Fig. 11 is a cross-sectional view taken on line 11-11 of the bracket sleeve and slide assembly shown in Fig. 10; and Figs. 12 and 13 show detailed views of the locking devices by which the frame of the loop may be secured in its extreme position outside of the cabinet structure.

Heretofore in the art in employing a loop antenna with a radio broadcast receiver it has been customary to mount the loop antenna in a fixed position within the apparatus cabinet. In this arrangement it has been very difficult to secure selective directive reception without changing the position of the entire cabinet.

Various mechanical arrangements have been proposed for rotating the loop within the cabinet structure but space within the cabinet is so limited that only a relatively small loop may be employed which in some instances may be inadequate for the most efficient reception. By my invention I provide a loop structure of relatively large size which may be normally housed adjacent the cabinet structure within the plane of one side of the cabinet and then readily removed by translatory motion to a position so far removed from the cabinet that rotative movement may be imparted to the frame structure for securing directive reception in a selected direction.

Referring to the drawings in more detail, reference character 1 designates the radio receiving apparatus cabinet structure having a horizontal bottom portion 2 on the lower side of which a block member 3 is mounted by means of bolt members 5 which secure the U shaped bracket members 6 around opposite sides of the sleeve member 7. The sleeve member 7 is rectangular in shape and provides a guide for a rectangular tube sliding member 11. The sleeve member 7 is apertured as represented at 10 through which a

spring latch 9 secured to a bracket member and limiting stop 8 is arranged to protrude. The bracket member 8 is secured to the outside wall of the hollow sleeve 7 adjacent the aperture 10. The sliding member 11 is provided with instruck projections 12 in one wall thereof with which the spring latch 9 is arranged to engage for locking the sliding member 11 in its extreme projecting position represented in full lines in Fig. 1. The sliding member 11 carries at its outer extremity the tubular member 14 disposed at right angles thereto. The tubular construction of the sliding member 11 enables the conductors 15 from the loop 20 to pass through the aperture 21 in the loop frame 19 and connect with the terminal block 4 on the underside of the radio receiving apparatus cabinet. The frame 19 of the loop is rectangular in shape and is braced across its lower portion, as represented at 17. Bearings 16 and 18 are supported at opposite points on the loop frame between which the tubular member 14 is journaled. In order to prevent any excess play at the rotating structure, I provide fiber gasket members 16^a and 18^a between the ends of the tubular member 14 and the bearings 16 and 18. Rotative movement of the loop may be secured through substantially 360°, which is sufficient for all practical purposes inasmuch as the position of the apparatus cabinet 1 may also be varied. Felt members 22 on the frame 19 provide abutment stops for the loop when in retracted position as represented in dotted lines in Fig. 1 for preventing the marring of the finish of the cabinet. The housing portion of the loop frame is indicated at 19' with the turns of the loop represented at 20'. In housing the loop the spring latch 9 is withdrawn from the aperture 10 enabling the abutment 12 to pass freely in the direction of the apparatus cabinet. Projection of the loop frame outwardly from the cabinet structure is limited by the projection of the spring latch 9 into the apertured portion of the sliding member 11.

It will be observed that connections between the loop antenna and the radio receiving apparatus within the cabinet are preserved at all times and that a wide selection for directive reception is available by the substantially free rotative movement which may be imparted to the loop structure.

While I have described my invention in a certain preferred embodiment, I desire it to be understood that modifications may be made and that no limitations upon my invention are intended other than are imposed by the scope of the appended claims.

What I claim as new and desire to secure by Letters Patent of the United States is as follows:

1. In a radio receiving apparatus including a radio cabinet, the combination of a tubular sleeve member supported with respect to said cabinet, a slidable tubular member carried by said sleeve member and a loop antenna pivotally mounted on one end of said slidable tubular member whereby connections between said radio cabinet and said loop antenna may be established by conductors passing through said tubular member. 75

2. In a radio receiving apparatus including a radio cabinet, the combination of a bracket member carried by said radio cabinet, a tubular member supported by said bracket member and apertured at one side thereof, a spring latch carried by said tubular member and arranged to normally project into the apertured portion thereof, a slidable tubular member arranged for reciprocative motion in said tubular member, a frame for a coil antenna and a pivotal connection between said frame and the outer extremity of said slidable tubular member whereby connections may be established between said coil antenna and said radio cabinet by conductors passing through said slidable tubular member while said coil antenna may be rotated through substantially 360°. 80

3. In a radio receiving apparatus including a radio cabinet, the combination of a horizontal tubular bracket supported with respect to said radio cabinet, a horizontal member arranged for reciprocative movement in said horizontal tubular bracket with substantially no rotation, a frame member, a coil antenna carried by said frame member, a shaft member secured adjacent the outer extremity of said horizontal member, said frame member being journaled on said shaft member whereby said frame may be moved away from said cabinet and swung through an arc of substantially 360° for selective directive reception. 95

In testimony whereof I affix my signature.

FREDERICK A. KOLSTER.
